UNITED STATES PATENT OFFICE.

HARRY H. STEPHENS, OF PATERSON, NEW JERSEY.

CENTRIFUGAL APPARATUS.

1,262,129.

Specification of Letters Patent.

Patented Apr. 9, 1918.

Application filed April 6, 1916. Serial No. 89,277.

To all whom it may concern:

Be it known that I, HARRY H. STEPHENS, a citizen of the United States, residing in the city of Paterson, State of New Jersey, have invented a new and useful Centrifugal Apparatus, of which the following is a specification.

My invention relates to centrifugal apparatus for the separation from each other of materials of different weights or of different characters, as liquids from solids, and particularly adaptable for the separation of oil from machined parts, metal chips, turnings, scrap, etc.

My invention resides in centrifugal apparatus wherein there is provided means for readily discharging the contents of the basket through the bottom thereof, such means comprising an unloading valve or removable basket bottom which is preferably moved downwardly for the purposes of discharge into a chute or the like.

My invention resides also in the combination with centrifugal apparatus of another centrifugal machine for filtering or otherwise acting upon the material separated by centrifugal action in the first named apparatus, the basket of the second machine being driven by the driving mechanism of the main centrifugal apparatus.

My invention resides in the features hereinafter described and claimed.

For an illustration of one of the forms my invention may take, reference is to be had to the accompanying drawings, in which:

Figure 1 is a vertical sectional view, some parts in elevation, through a form of apparatus embodying my invention.

Fig. 2 is a side elevational view, on smaller scale, of the apparatus shown in Fig. 1.

Fig. 3 is a horizontal sectional view, some parts in plan view, taken on the line 3—3 of Fig. 2.

On the base 1 are the pedestals 2 and the post 3 upon which are supported the chute 4 upon which is secured the bottom 5 of the curb 6. The base 1 has the upwardly extending hollow projection 7 in which is disposed the cylindrical rubber buffer 8 on whose upper edge rests the flange 9 of the metallic member 10 in which rests the metallic conical member 11 having the ball bearings 12 and 13 for the vertically extend-

ing shaft 14 on whose lower end is threaded the nut or washer 15 upon which rests the rotating lower member 16 of the lower ball bearing; and upon which member 16 rests the member 17 upon which rests the rotating member 18 of the upper ball bearing, the shaft 14 resting by a shoulder upon the member 18. The conical member 11 is closed at its bottom and the interior thereof is connected by oil tube 19 with a slight feed oil gauge and filler secured to side of chute 4, the interior of the bearing 11 being flooded with oil whose level is determined by the height of oil gage and filler.

Embracing the members 7 and 11 is the pulley 20 secured at 21 upon the shaft 14 for driving the same, a belt 22 driving the pulley 20. The shaft 14 extends upwardly through the upwardly extending portion 23 of the bottom of the chute 4. Above the member 23 is the spider 25 whose hub 26 is keyed at 27 to the shaft 14. The spider 25 carries at the upper ends of its arms the bottom 27 of the centrifugal basket 28 whose sides incline upwardly and outwardly. Secured to the inner circular edge of the bottom 27 is the valve seat ring 29 with which engages the conical member or valve 30 having the screw threaded sleeve 31 in which is threaded the sleeve 32 having the square or hexagonal head 33. The valve member 30 is prevented from rotating about shaft 14 by two keys 14^a secured to shaft 4. The center rim 30^a of member 30 is provided with keyways 14^b fitting over keys 14^a but allowing member 30 to move freely longitudinally of the shaft 14. The sleeve 32 is shouldered on its inside at 34 against a shoulder on the shaft 14 and the sleeve 32 is held against the shoulder 34 by the washer or nut 35 threaded upon the shaft 14. The shaft 14 extends upwardly freely through the central boss 36 on the basket cover 37 having the knobs or handles 38. The basket cover 37 and boss 36 rest upon the upper edge of basket 28 and top of washer or nut 35, respectively. Above the cover 37 is the hand wheel 39 whose hub 40 is threaded upon the upper end of the shaft 14 to press the cover 37 downwardly and hold the same in place. At 41, on the inside of the hub 40, is a square or hexagonal socket adapted to receive the square or hexagonal head 33 of the sleeve 32.

On the upper end of the curb 6 is secured the annular flange member 42 which supports the annular member 43 having the downwardly extending flange 44 overlapping and spaced from the upwardly extending flange 45 on the cover 37. On the ring member 43 are disposed the knobs or handles 46.

Communicating with the interior of the curb 6 at its bottom is the draw-off cock 47 through which liquid separated by centrifugal action may be drawn off into the centrifugal basket 48 having perforations and supplied with a filter lining in well known manner. The basket 48 is secured by its bottom 49 upon the upper end of the shaft 50 having a vertical bearing in the sleeve 51 in the vertically extending bearing block 52 supported by its base 53 upon the bracket 54 on the post 3. The shaft 50 rests on its lower end upon the ball 55 in an opening with which communicates the oil pipe 56 receiving oil from the cup 56^a for lubricating the bearing of the basket 48. Basket 48 is housed in the curb 57 supported on the bracket 58 on the post 3, and having the cover member 59. The filtered oil or liquid is drawn off from the curb 57 through the cock 60, Fig. 2.

On the basket bottom 49 is a sleeve 61 extending downwardly through the upturned annular flange 62 on the bottom of the curb 57. On the sleeve 61 is the pulley 63 driven by the belt 64, Figs. 2 and 3, which passes over and is driven by the pulley 65 secured to the idler pulley or wheel 66 which is pressed against and driven by the main belt 22. The pulley 65 and idler 66 are supported upon a stud 67 secured in the outer end 68 of the arm 69 whose other end 70 is pivoted upon the stud 71 carried by the bracket 54 and co-axial with the shaft 50 and the pulley 63. Through the upper end of the bracket 72, Figs. 2 and 3, secured upon the base 1 is a screw threaded rod 73 on which is threaded the hand wheel 74. One end of the rod 73 has a head 75, Fig. 3, having a spherical surface bearing in a spherical socket in the boss 76 upon the arm 69. Surrounding the rod 73 is the spring 77 which is under compression between the upper end of the bracket 72 and the web 78 of the arm 69. By turning the wheel 74 the arm 69 will be drawn toward the bracket 72, or if the wheel 74 is moved in opposite direction the spring 77 will force the arm 69 away from the bracket 72. By this means the idler 66 is adjusted as to its pressure against its driving belt 22, all movement of the arm 69 being pivotal about the stud 71.

Adapted to press against the face of the pulley 20 is the brake shoe 79 carried by the arm 80 secured upon the shaft 81 on which is secured the lever 82 having the foot

treadle 83. A spring 84 normally holds the brake shoe away from the face of the pulley 20.

The operation is as follows:

Assuming metal chips, turnings or small machine parts and oil adhering thereto to be the material to be treated for separating the oil and the metal parts, the material is charged into the basket 28 and the cover 37 placed thereon and thereafter the hand wheel 75 39 screwed on the upper end of the shaft 14 against the cover 37. Thereafter the ring member 43 may be placed in position illustrated.

The apparatus is then driven by the belt 80 22 and the basket 28 revolved at suitably high speed, with the result that by centrifugal force the oil is separated from the metal parts and accumulates on the basket 28 and flows up along its upwardly and outwardly inclined side and passes over its upper edge through the joint between its upper edge and the cover 37 into the curb 6, where it collects in the bottom of the member 5 and passes off through the cock 47 90 into the centrifugal basket 48 which is driven through the idler 66, pulley 65, belt 64, and pulley 63, the oil being operated upon by centrifugal force and passing outwardly through the filtering medium and 95 through the perforations in the drum 48 into the interior of the curb 57 from which it is drawn off from cock 60 in filtered and purified condition.

At the end of a run the wheel 39 is removed and thereafter the cover 37 with ring 43 resting thereon. Then the wheel 39 is used as a wrench, the square or hexagonal opening 41 being placed over the square or hexagonal head 33 of threaded sleeve 32. 105 Upon turning the wheel the sleeve 32 will rotate, but will maintain a fixed position longitudinally of the shaft 14. The rotation of the sleeve 32 drives the sleeve 31 downwardly, thereby lowering the valve or member 30 away from its seat 29 into the free space between the arms of the spider 25. This in effect opens the bottom of the basket and all of the solid contents thereof may be passed out through the opening 110 through which it falls into the chute 4 which delivers the solid material into any desired receptacle.

By reversing the operation the member 31 is restored to its normal position indicated, and a new charge of material may be introduced into the basket 28, the cover 37 replaced, the wheel 39 replaced in the position illustrated, ring 43 replaced, and the operation above described repeated.

What I claim is:

1. The combination with a rotary shaft, of a spider secured thereon, said spider comprising arms having upturned ends, a centrifugal basket, a bottom therefor secured to 120

said ends of said arms, said bottom having a central opening within said arms, a valve member adapted to close said opening, and means for moving said valve member downward into the space between the ends of said arms, to open said opening.

2. The combination with a rotary shaft, of a spider secured thereon, said spider comprising arms having upturned ends, a centrifugal basket, a bottom therefor secured to said ends of said arms, said bottom having a central opening within said arms, a valve member adapted to close said opening, said shaft extending into said basket, and means supported on said shaft within said basket for moving said valve member downward into the space between the ends of said spider arms, to open said opening.

3. The combination with a rotary shaft, of a spider secured thereon, said spider having arms with upturned substantially vertical ends, a centrifugal basket, a bottom therefor secured to said ends of said arms, said bottom having a central opening within said arms, a valve member adapted to close said opening, and means to open said opening comprising means for moving said valve member downwardly into the space between the ends of said arms.

4. The combination with a centrifugal basket, of a bottom therefor, having a central opening for discharge of load, means for normally closing said opening, a spider support for said basket having a central hub, a chute beneath said basket for receiving the load discharged through said opening, a rotary shaft for said basket passing through said chute and said hub, the opening through said chute being greater in diameter than that of the shaft and less in diameter than that of the hub, and a collar for said opening in said chute extending upwardly to said hub, whereby the hub prevents any portion of the load, upon discharge, from passing through said opening in said chute.

5. The combination with a centrifugal basket, of a curb therefor, a bottom for said basket having an opening therethrough for discharge of load, a spider support for said basket having a central hub portion, a chute beneath said basket for receiving the load discharged, a vertical rotary shaft for said basket passing through an opening in said chute and an opening in said hub portion, the diameter of the opening in said chute being greater than that of the shaft, a recess in the bottom of said hub portion around said shaft, an upturned collar for said opening in said chute extending into the recess in said hub, whereby a portion of the load is prevented, upon discharge, from passing through the opening in said chute.

6. The combination with a rotary shaft, of a spider secured thereon, said spider comprising arms, a centrifugal basket, a bottom therefor secured to the outer ends of said arms, said bottom having a central opening within said arms, a valve member adapted to close said opening, the lower portion of said opening having sloping walls, and means for moving said valve member downwardly to discharge the contents of the basket, the sloping walls of the valve serving to receive and direct the discharge.

7. The combination with a rotary shaft, of a spider secured thereon, said spider comprising arms having upturned ends, a centrifugal basket, a bottom therefor secured to said ends of said arms, said bottom having a central opening within said arms, a valve member adapted to close said opening, means for moving said valve member into the space between said arms, said valve member being limited in its upward travel by said bottom and in its downward travel by said arms.

In testimony whereof I have hereunto affixed my signature this 4th day of April, 1916.

HARRY H. STEPHENS.
